METHOD AND APPARATUS FOR CLEANING
FURNACE CHECKERS AND FLUES

William J. Montgomery, Warren, Ohio

Application August 20, 1945, Serial No. 611,602

17 Claims. (Cl. 263—19)

1

This invention relates to improvements in a method and apparatus for cleaning furnace checkers and flues, and has for its primary object the removal of flue dust and debris from the checkers and flues.

Another object is to carry the flue dust and debris to the base of the furnace stack pit or uptake and deposit it on the floor of the furnace stack pit or uptake.

Another object is to remove the flue dust and debris from the floor of the furnace stack pit or uptake either automatically or by hand without interrupting the operation of the furnace.

The above and other objects may be attained by employing this invention which embodies among its features directing a fluid blast against and through the furnace checkers to remove flue dust and debris, suspending the flue dust and debris so removed on a moving fluid blast directed toward the base of the stack pit or uptake of the furnace, depositing the flue dust and debris on the floor of the stack pit or uptake of furnace, isolating the flue dust and debris so deposited from the rest of the stack pit or uptake so that it may be removed without interrupting the operation of the furnace.

Other features embody conduits mounted atop the checkers or at any elevation of the checkers having nozzles for directing a blast of fluid against or through the checkers, conduits extending longitudinally of the side walls of the furnace flues and having nozzles directed in such a manner as to suspend the flue dust and debris loosened from the checkers on a fluid blast which moves toward the base of the stack pit or uptake of the furnace, and doors adapted to be moved into a position to isolate the flue dust and debris which is deposited on the floor of the stack pit or uptake by the moving blast so that removal of the flue dust and debris from the floor of the stack pit or uptake may progress without interrupting the operation of the furnace.

Other features include removing the flue dust and debris from the floor of the stack pit or uptake by vacuum, and water-cooling the isolating doors, not only to protect them from the intense heat at the base of the stack pit or uptake, but also to reduce the temperature in the isolated area of the furnace stack pit or uptake to protect workmen who may enter the isolated area for the removal of the debris by hand.

In the drawings:

Figure 1 is a horizontal sectional view through a regenerative furnace showing the checker chambers and flues leading to the stack,

Figure 2 is a longitudinal sectional view taken substantially on the line 2—2 of Figure 1,

Figure 3 is a horizontal sectional view taken substantially on the line 3—3 of Figure 2,

Figure 4 is a vertical sectional view taken substantially on the line 4—4 of Figure 2,

2

Figure 5 is an enlarged sectional view taken substantially on the line 5—5 of Figure 1,

Figure 6 is a vertical sectional view taken substantially on the line 6—6 of Figure 5,

Figure 7 is a fragmentary enlarged horizontal sectional view through the base of a stack and a portion of the flues leading thereto showing a modified form of isolating door arrangement,

Figure 8 is a transverse sectional view taken substantially on the line 8—8 of Figure 7,

Figure 9 is a sectional view taken substantially on the line 9—9 of Figure 7,

Figure 10 is an enlarged transverse sectional view through one of the blast conduits and its nozzle,

Figure 11 is a transverse sectional view taken substantially on the line 11—11 of Figure 5.

Figure 12 is an enlarged detail sectional view taken substantially on the line 12—12 of Figure 3,

Figure 13 is a fragmentary longitudinal sectional view taken substantially on the line 13—13 of Figure 12, and

Figure 14 is an enlarged detail fragmentary sectional view through the base of a furnace stack or uptake showing a modified form of isolating door and debris-receiving pit.

Referring to the drawings in detail, a furnace designated generally 20 of the regenerative type is provided with the usual hearth 21 (Fig. 2) in which the combustion of the mixed gases leaving a mixing chamber 22 takes place. Leading to the mixing chamber are the usual air and gas conduits 23 and 24, respectively, which in turn communicate at their lower ends with the usual checker chambers 25 and 26 containing walls 27 of checker brick. The check chambers 25 and 26 communicate at their ends opposite the air and gas conduits 23 and 24 with flues 28 which lead to a stack 29. The furnace is provided with the usual reversing valves 30 (Fig. 1) and the arrangement of the various passages for the air and gas supply is of conventional form, following that ordinarily employed in regenerative furnaces of the type to which this invention relates.

Mounted atop the checker walls 27 in respective checker chambers 25 and 26 are blast pipes or conduits 31 provided at spaced intervals with downwardly directed nozzles 32 which are so arranged that a blast of fluid is directed against

the side faces of the checker walls 25 and 26 to loosen flue dust and debris and cause it to be blown downwardly into the flues 28. These blast pipes 31 are protected from the intense heat generated within the checker chambers, first, by a

layer of asbestos 33 of not too dense a form so as to allow for expansion and contraction of the pipes 31 under the influence of temperature.

Surrounding the exterior of the asbestos covering 33 of the pipes 31 is a loosely packed insulating substance preferably of a finely divided nature, such as Sil-o-cell 34, which in turn is held

in place by an outer ceramic cylindrical shell 35 formed of a suitable material, such as silica brick, and the entire insulated piping unit is supported atop the checker walls by a suitable ceramic structure 36 which may take the form of rectangular slabs, as illustrated in Figures 4 and 12.

The pipes 31 lead outwardly through the end walls of the checker chambers 25 and 26 and are connected to a header 37 which in turn is connected through a valve 38 to a pressure supply line 39 which may be connected to a source of pressure supply, such as an air pressure reservoir or in other instances it may be found desirable to connect the pipe 39 to a source of high pressure steam. As illustrated in Figure 3, the pressure line 39 is connected through a two-way valve 40, which leads through branch pipes to the valve 38, so that one or the other set of checker chambers on opposite sides of the furnace may selectively be cleaned. As illustrated in Figure 3, the pressure supply line 39 is provided with a lead which extends into each checker chamber on opposite sides of the furnace and is provided with a return bend 41 so that the fluid passing through the pipes will be super heated before it enters the header 37 and blast pipes 31. A suitable shut-off valve 42 is arranged to control the flow of fluid through the supply pipes 39 and in some instances I find it desirable to introduce a pressure-reducing valve 43, and suitable strainers 44 according to the requirements of the particular installation.

Built longitudinally along each flue 28 at the junction of its floor and its vertical side walls of suitable heat-resisting material, such as silica brick, is a guard or housing 45 provided with a vertical curb 46, which curbs cooperate to form a longitudinally extending well or trough 47 in each such flue. Each housing 45 is formed with a longitudinally extending chamber 48 containing a suitable insulating material 49 which surrounds a blast pipe or conduit 50. This blast pipe or conduit is provided at spaced intervals with blast nozzles 51 which are directed outwardly and at any desired angle, through the curb 46 and is surrounded by a suitable thermal insulation 52. The nozzles 50 are preferably placed at such an angle as to cause the fluid blast issuing therefrom to be directed in the general direction of the stack 29 so that a longitudinal flow of the fluid issuing from the jet 51 will be toward the stack. These pipes 50 are connected through the medium of risers 53 to the pressure supply line 39, and so arranged as to be separately controllable through valves 54 arranged at suitable points in the system.

Formed at the junction of the floor 55 and the side walls and back wall 56 and 57, respectively, of the base of the stack 29 is a curb 58 forming a well 59 into which the flue dust and debris is deposited. Blast pipes 60 are embedded in the curb 58 and are provided with nozzles 61 leading outwardly through the side wall of the curb toward the interior of the well 59. These blast pipes 60 are connected in any suitable manner to the pipe 39 leading from the source of fluid pressure and suitable valves (not shown) are interposed for the purpose of regulating the flow of fluid into the pipes 60. Formed in the floor of the stack approximately mid-way between the sides and ends of the well or pit 59 is an opening 63 through which a discharge pipe 64 extends. This discharge pipe is connected through a riser 65 with an exhaust fan 66, which in turn is connected to a pipe 67 with a suitable receptacle for

the reception of the flue dust and debris which may be exhausted from the base of the stack through the pipe 65 and fan 66.

Extending diagonally from the upper end of the back wall 57 of the base of the stack to the lower end of the arch 68, which establishes connection between the flue 28 and the stack 29, and against opposite side walls 56 of the base of the stack, are inclined channels 69. Welded or otherwise secured to the inner faces of the webs of the channels 69 are angles 70 which extend upwardly beyond the ends of the channels, as illustrated in Figure 5, and are supported at their extreme upper ends on suitable pedestals 71. These channels 69 and angles 70 form guides for supporting a door frame 72 carrying a layer of insulating brick 73 which forms the door for isolating the floor 55 and well or pit 59 of the stack 29 from the stack when the flue dust and debris is to be removed from the base thereof. In instances where it is desired to provide cooling for the door 73 and the isolated portion of the stack 29, the insulating brick is provided with longitudinal passages for the reception of cooling fluid-receiving pipes 74 which are connected together in such fashion as to permit the flow of cooling fluid therethrough. Carried adjacent the door 73 by the channels 69 are suitable conduits 75 which are preferably embedded in a suitable supporting material 76, and these pipes 75 are likewise connected with the source of cooling fluid so that additional cooling may be provided for the isolated portion of the stack and the channels 69 further protected against the intense heat from the furnace. Carried at the upper end of the door frame 72 is an ear 77 to which a suitable elevating cable 78 is attached. This cable is carried over a sheave 79 supported in any suitable manner on a bracket 80 and the cable 78 is connected to any suitable type of winding drum (not shown) by means of which the door frame 72 and the insulating brick carried thereby may be lifted during the normal operation of the furnace.

In the modified form of stack floor-isolating mechanism illustrated in Figures 7 to 9, inclusive, I provide adjacent the stack base a pit 81 and extending horizontally across the arch 68 at its lower end is a channel 82. This channel extends into the pit 81, as illustrated in Figure 7, and has mounted therein at spaced intervals angles 83 for a purpose to be more fully hereinafter described. A similar channel 84 extends horizontally across the back wall 57 of the base of the stack and into the pit 81 substantially on a level with the upper end of the arch 68. Like the channel 82, the channel 84 is provided with an angle 85 for a purpose to be more fully hereinafter described. Extending between the channels 82 and 84 are isolating doors 86 carrying at opposite ends rollers 87 which ride on the flanges of the channels and the angles to facilitate easy movement of the doors into open or closed position. Like the door 73, the doors 86 may also be provided with suitable cooling fluid conduits 88 for the circulation of cooling fluid therethrough.

Alternatively to the form of doors illustrated in Figures 5 to 9, inclusive, there are instances when I find it desirable to employ at the base of the stack 29 a structure such as that illustrated in Figure 14. In such a case I provide at the base of the stack a pit 90 on the upper ends of the side walls of which I support a door 90 on suitable rollers 91 which enable the door 90 to be withdrawn from its position beneath the stack so that flue dust and debris will be deposited in

the pit 89. In order to facilitate the easy removal of such material from the pit, I provide a carriage 92 in the form of a receptacle which may be readily moved from its position beneath the lower end of the stack by movement on rollers 93 in a horizontal direction. It will be understood, of course, that a suitable pit is arranged adjacent the pit 89 for the reception of the carriage 92.

In operation, it will be understood that when a certain checker chamber or flue is to be cleaned, the proper valves are opened to direct the fluid blast from the pipes 39 through the superheaters 41 to the header 37 and thence into the pipes 31 resting atop the checkers. The fluid issuing through the nozzles 32 will be directed against the sides of the checker and down through checker openings so as to loosen any flue dust and debris and direct it downwardly into the flue 28 with which the checker chamber is connected. Simultaneously with the dislodgment of the flue dust and debris from the checkers under the influence of the fluid blast issuing from the nozzles 32 pressure is admitted through the risers 53 in the proper flue 28 so as to create a fluid blast in the well or wells 47 of the flue passage which is being cleaned. Due to the angular disposition of the nozzles 51 leading from the blast pipe 50 at the bottom of the flue 28 a fluid blast will be created which moves the flue dust and debris toward the stack 29. Rising at the stack 29 and at the end of the creation of the fluid blast, upon which the flue dust and debris have been sustained, the flue dust and debris will deposit on the floor of the stack until a sufficient quantity has been accumulated to warrant its removal. The isolating door 12 or 86, as the case may be, is then closed so as to isolate the area upon which the flue dust and debris have been deposited from the rest of the stack, after which the removal of the flue dust and debris from the floor 55 of the stack may proceed, either by hand or automatically, by operating the exhaust fan 66 and discharging the flue dust and debris through the pipes 64 and 67 to any suitable receptacle. It is to be noted that the isolation of the floor of the stack does not interrupt the flow of heated gases through the stack, though some constriction of the passage result. Such constriction is not serious, however, and enables the furnace to be operated continuously without interrupting production for cleaning purposes.

The flue cleaning process may be carried on continuously with the operation of the furnace by employing the pressure-reducing valve 43, which, while causing the fluid blast to serve somewhat as a booster to the stack draft, at the same time so regulates the pressure of the blast as to avoid interference with the furnace operation. Under such conditions of continuous operation, it is only necessary periodically to manipulate the doors 12 or 86 so as to isolate the floor of the stack from the rest of the stack during the time that the stack cleaning is in progress. The operation of the structure illustrated in Figure 14 is essentially the same as that previously described, except that the door 90 operates in a horizontal rather than an inclined plane, and the carriage 92 forms a receptacle for the reception of the flue dust and debris, which receptacle may periodically be withdrawn from its position beneath the stack when the door 90 is closed so that it may be emptied at leisure. Doors or dampers (not shown) may be introduced in the

system at suitable points to effect the desired flow of fluids therethrough.

While in the foregoing there has been shown and described the preferred embodiment of this invention, it is to be understood that minor changes in the details of construction, combination and arrangement of parts may be resorted to without departing from the spirit and scope of the invention as claimed.

10 I claim:

1. The herein described method of cleaning furnace checkers and flues which includes directing a fluid blast against the checkers to dislodge flue dust and debris therefrom, collecting the flue dust and debris so dislodged on the floor of the furnace stack, isolating the portion of the floor of the stack upon which the flue dust and debris is collected, and removing the flue dust and debris from the isolated area.

20 2. The herein described method of cleaning furnace checkers and flues which includes directing a fluid blast against the checkers to dislodge flue dust and debris therefrom, conveying the flue dust and debris so dislodged to the base of the furnace stack, collecting the flue dust and debris on the floor of the furnace stack, isolating the portion of the floor of the stack upon which the flue dust and debris is collected, and removing the flue dust and debris from the isolated area.

25 3. The herein described method of cleaning furnace checkers and flues which includes directing a fluid blast against the checkers to dislodge flue dust and debris therefrom, creating a fluid blast in the furnace flues which moves toward the stack of the furnace, conveying the flue dust and debris by said fluid blast to the base of the stack, collecting the flue dust and debris on the floor of the stack, isolating that portion of the floor of the stack upon which the flue dust and debris is collected, and removing the flue dust and debris from the isolated area.

30 4. The herein described method of cleaning furnace checkers and flues which includes directing a fluid blast against the checkers to dislodge flue dust and debris therefrom, collecting the flue dust and debris so dislodged on the floor of the furnace stack, isolating the portion of the floor of the stack upon which the flue dust and debris is collected, and extracting the flue dust and debris from the isolated area under the influence of vacuum.

35 5. The herein described method of cleaning furnace checkers and flues which includes directing a fluid blast against the checkers to dislodge flue dust and debris therefrom, conveying the flue dust and debris so dislodged to the base of the furnace stack, collecting the flue dust and debris on the floor of the furnace stack, isolating the portion of the floor of the stack upon which the flue dust and debris is collected, and extracting the flue dust and debris from the isolated area under the influence of vacuum.

40 6. The herein described method of cleaning furnace checkers and flues which includes directing a fluid blast against the checkers to dislodge flue dust and debris therefrom, creating a fluid blast in the furnace flues which moves toward the stack of the furnace, conveying the flue dust and debris by said fluid blast to the base of the stack, collecting the flue dust and debris on the floor of the stack, isolating that portion of the floor of the stack upon which the flue dust and debris is collected, and extracting the flue dust and debris from the isolated area under the influence of vacuum.

7. The herein described method of cleaning furnace checkers and flues which includes periodically isolating certain of the checker chambers and flues of a furnace from other checker chambers and flues of the furnace, directing a fluid blast against the isolated checkers and along the isolated flues toward the stack of the furnace, collecting the flue dust and debris dislodged and carried by the fluid blast on the floor of the stack, without arresting the flow of heated gases from the unisolated flues and checkers of the furnace, isolating that portion of the floor of the stack upon which the flue dust and debris is collected, and removing the flue dust and debris from the isolated area of the stack.

8. The herein described method of cleaning furnace checkers and flues which includes periodically isolating certain of the checker chambers and flues of a furnace from other checker chambers and flues of the furnace, directing a fluid blast against the isolated checkers and along the isolated flues toward the stack of the furnace, conveying by the fluid blast the flue dust and debris dislodged thereby along the flues toward the base of the stack of the furnace, collecting the flue dust and debris on the floor of the stack, without arresting the flow of heated gases from the unisolated flues and checkers of the furnace, isolating that portion of the floor of the stack upon which the flue dust and debris is collected, and extracting the flue dust and debris from the isolated area under the influence of vacuum.

9. The herein described method of cleaning furnace checkers and flues which includes directing a fluid blast against the checkers to dislodge flue dust and debris therefrom, collecting the flue dust and debris so dislodged on the floor of the furnace stack, isolating the portion of the floor of the stack upon which the flue dust and debris is collected, decreasing the temperature within the isolated portion of the stack, and removing the flue dust and debris from the isolated area.

10. The herein described method of cleaning furnace checkers and flues which includes periodically isolating certain of the checker chambers and flues of a furnace from other checker chambers and flues of the furnace, directing a fluid blast against the isolated checkers and along the isolated flues toward the stack of the furnace, collecting the flue dust and debris dislodged and carried by the fluid blast on the floor of the stack, without arresting the flow of heated gases from the unisolated flues and checkers of the furnace, isolating that portion of the floor of the stack upon which the flue dust and debris is collected, decreasing the temperature within the isolated portion of the stack, and removing the flue dust and debris from the isolated area.

11. In a system for cleaning furnace checkers and flues, the combination with a furnace which includes checker chambers, checkers in said checker chambers, a stack and flues establishing communication between the checker chambers and the stack, of means to create a blast of fluid against the checkers and along the flues to dislodge flue dust and debris from the checkers and to convey it along the flues to the floor of the stack, and means to isolate the portion of the stack in which the flue dust and debris collects whereby removal of the flue dust and debris from the isolated area of the stack may progress without interference from the heated gases passing through the stack.

12. In a system for cleaning furnace checkers and flues, the combination with a furnace which includes checker chambers, checkers in said checker chambers, a stack and flues establishing communication between the checker chambers and the stack, of means selectively to isolate certain checker chambers and flues from other chambers and flues of the furnace, means for creating an air blast against the checkers in the isolated checker chambers to dislodge flue dust and debris therefrom, means for creating an air current through the isolated flues upon which the flue dust and debris is conveyed toward the base of the stack and by which it is collected and deposited on the floor of the stack, and means to isolate only that part of the stack containing the flue dust and debris from the remainder of the stack whereby the flue dust and debris may be removed without interfering with the flow of heated gases into the stack.

13. In a system for cleaning furnace checkers and flues, the combination with a furnace which includes checker chambers, checkers in said checker chambers, a stack and flues establishing communication between the checker chambers and the stack, of means to create a blast of fluid against the checkers and along the flues to dislodge flue dust and debris from the checkers and to convey it along the flues to the floor of the stack, means to isolate that portion of the stack in which the flue dust and debris collects, and means to decrease the temperature in the isolated portion of the stack.

14. In a system for cleaning furnace checkers and flues, the combination with a furnace which includes checker chambers, checkers in said checker chambers, a stack and flues establishing communication between the checker chambers and the stack, of means selectively to isolate certain checker chambers and flues of the furnace, means for creating an air blast against the checkers in the isolated checker chambers to dislodge flue dust and debris therefrom, means for creating an air current through the isolated flues upon which the flue dust and debris is conveyed toward the base of the stack and by which it is collected and deposited on the floor of the stack, means to isolate only that part of the stack containing the flue dust and debris from the remainder of the stack, and means to cool the isolated portion of the stack.

15. The combination with means for dislodging and conveying flue dust and debris from furnace checkers and depositing said flue dust and debris on the floor of the stack of the furnace, of a door adapted to partially close the stack to isolate the floor from the remainder of the stack whereby removal of the flue dust and debris can progress without interfering with the operation of the furnace.

16. In combination with a furnace stack, a door adapted to be moved into a position to isolate the floor of the stack from the balance of the stack, and means to support the door in open or closed position.

17. A door for isolating one part of a furnace stack from another part of said stack which includes a pair of spaced guides so positioned near the base of the stack that when the door is closed it lies at such an angle to the major axis of the stack as to allow the free passage of flue gases through the stack, and means to open or close said door.

WILLIAM J. MONTGOMERY.
